GLOVE

Sylvan M. Straus, Gloversville, N. Y.

Application February 19, 1934, Serial No. 711,876

3 Claims. (Cl. 2—162)

My invention relates to a new and improved glove and a new and improved method of making the same.

One of the objects of my invention is to provide a glove having an extensible wrist portion.

Another object of my invention is to provide a glove whose wrist portion is fluted and extensible.

Another object of my invention is to provide a glove having an extensible wrist portion, by sewing elastic thread or threads to the exterior of the glove, in order to provide a suitable ornamental appearance and to eliminate the use of elastic inserts so that the interior of the glove 15 does not have any inwardly projecting portions.

Other objects of my invention will be set forth in the following description and drawing which illustrates a preferred embodiment thereof, it being understood that the above statements of the 20 object of my invention is intended to generally explain the same without limiting it in any manner.

Fig. 1 is a plan view of the improved glove.

Fig. 2 is a detail plan view showing how the 25 wrist portion of the glove is extended.

Fig. 3 is a sectional view on the line 3—3 of Fig. 1.

Fig. 4 is a perspective view which illustrates the elastic thread which is used, this view being 30 very much enlarged.

It has heretofore been proposed to make the wrist portion of a glove elastic and extensible, by providing elastic tapes or the like which were located at the interior of the glove or which were 35 located in pockets which were provided in the glove. Such constructions were undesirable because they spoiled the ornamental appearance of the glove and they added to the thickness or bulk of the glove at the wrist portion.

40 The improved construction is applied to a glove of any suitable material such as leather or the like.

In the preferred embodiment, I provide two 45 pairs of elastic threads 12, the threads of each pair being spaced from each other and said pairs being also substantially spaced from each other. The distance between the pairs of threads exceeds the distance between the threads of each pair.

50 The elastic threads 12 are made of any suitable elastic material and I prefer to use the well known "Lastex" material.

As diagrammatically shown in Fig. 4, said "Lastex" thread has a core 12a made of rubber 55 or the like, which is covered by a helical winding

of any suitable yarn, such as silk, cotton or the like.

These "Lastex" threads can be applied by a suitable sewing machine. The "Lastex" threads are sewed around the wrist portion of the glove 5 and up to the slit in said wrist portion, while said "Lastex" threads are maintained under tension. When the tension is released, said threads contact so as to form flutes 13.

If the glove does not have a wrist slit at its 10 inner side, said "Lastex" threads 12 may be sewed either entirely around the wrist portion of the glove, or at any desired part or parts thereof.

Fig. 2 illustrates how the wrist portion of the glove can be transversely stretched until the 15 flutes 13 have disappeared.

The stretch of the wrist portion can be from one-third to one-half of its cross-sectional dimension, when the wrist portion is in its position of maximum contraction. This provides for 20 sufficient stretch to enable the hand of the user to be readily inserted and the wrist portion of the glove then has a snug fit.

The elastic threads 12 are wholly separated from each other. That is, they are not connected 25 by cross threads or the like so that the material of the glove can be freely puckered or fluted, intermediate each said pair of threads 12.

As shown in detail in Fig. 2, the elastic stitch which is produced by the threads 12, comprises a 30 series of interlocking loops L, said loops being wedge-shaped.

At the inner surface of the glove, the threads 12 are substantially flush with said inner surface, so that the bulk of the glove at its inner surface 35 is not increased to any objectionable extent. At the outer surface of the glove, the loops 12 project substantially and they can be made of a color which contrasts with the color of the material of the glove, in order to provide an ornamental 40 effect.

A glove of this type can be very readily and cheaply constructed and it is as comfortable as the ordinary glove, while giving the desired stretch and elasticity at the wrist portion. The rows of elastic stitches are preferably perpendicular to the longitudinal axis of the glove, but any suitable angle may be utilized.

The elastic threads can be applied to the trunk 50 or glove blank while it is in the flat condition, and the sewing of the glove blank can then be completed.

While I have shown four rows of elastic stitches, I can utilize any desired number of such rows, 55

either one or more, and I do not wish to exclude from the scope of the invention, the use of rows of parallel stitches, which may be transversely connected by transverse stitch members.

5 Likewise I do not wish to exclude from the scope of the invention, the use of elastic stitches which may project slightly from the interior surface of the glove although I prefer to use stitches which project much more from the exterior surface of the glove, than from its interior surface.

10 Referring to Fig. 1, the distance between the top row of stitches 12 and the bottom row of stitches 12 should be about one-half the total length of the wrist portion, and the top row of 15 stitches 12 may be directly adjacent the wrist joint portion of the glove.

The material of the glove may be specified as being fluted or normally fluted, adjacent the elastic stitches, as this is the normal condition

20 which is illustrated in Fig. 1.

I have shown a preferred embodiment of my invention, but it is clear that numerous changes and omissions can be made without departing from its spirit.

I claim:

1. A glove having a wrist portion, said wrist portion having transverse looped stitches made of elastic thread and which engage the material of said wrist portion, the material of said wrist portion being held normally fluted by said stitches, said stitches projecting more from the outside surface of the glove than from the inner surface of the glove.

2. A glove having spaced rows of elastic looped 10 stitches which engage the material thereof, the front row of elastic stitches being substantially adjacent the wrist-joint portion of the glove, the material of the glove being held normally fluted by said stitches, said stitches projecting more 15 from the exterior surface of the glove than from its interior surface.

3. A glove having a wrist portion, said wrist portion having connected looped stitches made of elastic thread and connected by the loops of said 20 stitches to the material of said wrist portion, the material of said wrist portion being held normally fluted by said stitches.

SYLVAN M. STRAUS.
